UNITED STATES PATENT OFFICE.

TITO L. CAVALLI, OF BENICIA, CALIFORNIA.

MILK-BOTTLE CONTAINER.

Application filed May 18, 1927. Serial No. 192,383.

This invention relates to improvements in milk bottle containers and has particular reference to a container adapted to be located at a customer's residence, for the purpose of receiving both full and empty milk bottles.

Another object of this invention is to produce a device wherein the delivery man may deposit a filled bottle in an open rack, and then move the rack in such a manner as to place the filled bottle within an enclosure for protection against dirt and sunlight.

A further object is to produce a device of this character which is simple in construction and therefore one which may be placed at the customer's door without extra charge to the customer.

A still further object is to provide a device of this character which will not delay the milkman in his delivery.

20 A still further object is to produce a device which will encourage the return of empty bottles and will also tend to prevent breakage which ordinarily occurs.

25 A still further object is to provide a device which is simple, neat in appearance, and economical to manufacture.

Other objects and advantages will be apparent during the course of the following description.

30 In the accompanying drawings forming a part of this specification and in which like numerals are employed to designate like parts throughout the same,

Figure I is a side elevation of my device, partly broken away, and

Figure II is a top plan view of Figure I, partly broken away.

In the delivery of milk to residences, it is common practise to set the bottles upon the customer's doorstep, which bottles are often-times left for a considerable period of time, with the result that dirt will accumulate upon the bottle cap, and if the milk is exposed to the sun, the milk is apt to be soured.

45 It has also been found that a large amount of bottles are broken due to the fact that the same are accidentally knocked over and roll down the steps. This breakage will be entirely prevented by the use of my device.

50 In the accompanying drawings wherein for the purpose of illustration is shown a pre-

ferred embodiment of my invention, the numeral 5 designates a baseboard to which is attached side boards 6 and 7. The side boards 6 and 7 are connected by a top board 8.

55 Slidably positioned upon the baseboard 5 is a crate-like structure having a bottom piece 9 and end pieces 11, and 12. These end pieces are connected by slats as shown at 13 and 14 and 16. A division board is shown at 17.

60 It will be noted that the end pieces 11 and 12 are of the same width as the baseboard 5, with the result that as the crate-like structure is moved from the full line position of Figure I to the dotted line position of this figure, the projecting portions 18 and 19 of the end pieces will act as stops when they come into contact with the side pieces 5 and 6.

65 In use, a customer places an empty bottle, as for instance in the section A of the crate-like structure. The delivery man will remove the empty bottle from the section A and place a filled bottle therein. Assuming that the crate like structure is in the position shown in full lines in Figure I, he will then 70 move the crate-like structure toward the right of the drawing so that the filled bottle will be in the section B and thus protected against the elements and any foreign substances.

75 It is to be noted that openings 10 are provided in the division wall 17, which serve to make the device in the nature of a cooler and permit the air to circulate through the device.

80 The customer may remove the bottle at any desired time and replace the same with an empty bottle. The crate may be moved to either side of the device depending upon which is the most convenient.

85 It is to be understood that the form of my invention herewith shown and described, is to be taken as a preferred example of the same and that various changes relative to the shape, material, size and arrangement of 90 parts may be resorted to without departing from the spirit of the invention or the scope of the subjoined claim.

95 Having thus described my invention, I claim:—

100 In a bottle holder a baseboard, sideboards secured to said baseboard, a topboard con-

necting said sideboards, a slidably crate-like structure positioned between said sideboards and slideable on said baseboard, said crate-like structure being of less length than said baseboard, the ends of said crate-like structure being of a length equal to the width of said baseboard, a division board positioned in

10
said box-like structure, the ends of said end pieces projecting beyond the sides of said crate-like structure for the purpose of acting as stops when said crate-like structure is moved on said base-board.

In testimony whereof I affix my signature.

TITO L. CAVALLI.
